UNITED STATES PATENT OFFICE

2,160,455

AIRPLANE

Charles Roger Anne Marie de Rougé, Mercues,
France, assignor to Pollopas Patents Limited,
London, England, a corporation of Great Britain

Application February 11, 1937, Serial No. 125,203
In Germany February 19, 1936

4 Claims. (Cl. 244—83)

The present invention relates to airplanes provided with a steering- and stabilizing plane arranged above the supporting plane and adapted to be swung about an axis mounted in a direction vertically to the direction of flight, and refers more particularly to stabilizing planes of this kind which may be adjusted and fixed in any position between a horizontal plane and a plane extending normally to the latter. This steering- and stabilizing plane is arranged at a distance from the supporting plane which is about twice as great as or greater than the depth of the supporting plane.

This steering- and stabilizing plane may replace the horizontal rudder, its action may, however, be limited to be used as a safety member besides the usual steering- and stabilizing members of flying machines in which case the steering members may or may not cooperate.

Particularly in the case in which the steering- and stabilizing plane cooperates with the other steering members of airplanes, dirigible balloons, lifting screws, etc., a further development of the plane has proved to be of advantage. This improvement consists in subdividing and so constructing the steering and/or stabilizing plane that each portion of same may, independently of the others, be adjusted or swung in any position between the horizontal plane and a plane extending under an angle of 90° thereto and be fixed in each adjusted position.

The individual portions of the plane may be fixed to a common axis or to different axes. They may be provided with control members which partly or completely are independent of each other. In their original position or the position of rest the portions of the plane preferably supplements a plane which, aside from unimportant details, has a continuous contour.

Finally it is possible to provide only two specially formed portions of the steering plane symmetrically with respect to each other which portions may be controlled independently of each other. Consequently the effects of the upper wings of coleopterans (May-bugs, stag-beetles) may be obtained. According to the problem which the constructor in each case intends to apportion to the planes he will choose the place of attachment of the planes.

In the accompanying drawings some constructions according to the invention are shown by way of example.

In these drawings:

Fig. 1 diagrammatically shows a side elevation of two planes mounted upon the same axis one

of which is directed rearwardly, the other forwardly,

Fig. 2 illustrates a side elevation similar to Fig. 1 of a modified construction.

Fig. 3 is a side elevational view which shows the use of three planes pivoted together in tandem on two axes.

Fig. 4 is a view in perspective of a plane, having three planes arranged side by side upon a common axis, but separately controlled, and shown in different positions.

Fig. 5 is a view in perspective of a plane, showing the use of two planes pivotally mounted upon independent axes, provided with ball joints.

As shown in Fig. 1, the two planes 2 and 3 of an airplane may independently be swung around the axis 1 to occupy for instances the positions 2', 2'' and 3', 3'', 3''' respectively shown in dotted lines.

In the modification shown in Fig. 2, the portions 5 and 7 of the plane of an airplane are independently mounted upon the axis 6. Due to their form these portions in the position of rest practically form a plane 4 continuous in its outer contour. The plane 5 according to this construction generally remains in its position of rest, whereas the plane 7 may be swung about an angle of 90° downwardly from the horizontal position. Essential parts of the control or adjusting members for the plane 7 may be located in the plane 5.

According to Fig. 3 the planes 10, 11 and 12 are mounted upon axes 8 and 8'. The plane 10 may be swung relative to plane 11 around the axis 8, whereas the plane 12 may be swung relative to plane 11 around the axis 8'. Positions of adjustments of the plane 10 around the axis 8 and the plane 12 around the axis 8' are shown at 10' and 12' respectively. The plane 11 and thereby the whole arrangement of the planes 10, 11 and 12 may be swung around the axis 9. For this purpose the control member 13 is provided which partially extends through the main supporting plane 14, which is the supporting mast 14 for the axis 9. The other control members for swinging the planes are not shown in the drawing.

In the modification shown in Fig. 4 the planes 17, 18 and 19 of an airplane may independently of each other be adjusted around the common axis 16 by means of the control members 21, 21' and 22, 22' for the planes 17 and 19 respectively. In the position of rest the planes 17, 18 and 19 form a single plane 15. The swung out portions are designated with the reference character 15.

From the drawings it is at once to be seen, that the planes 17, 18 and 19 may independently of each other be adjusted in any inclined position. The control member 20 below the plane 18 is also pivoted on the main supporting plane, which allows swinging of the entire steering and/or stabilizing plane.

According to Fig. 5 an axle 23 journalled for instance in a ball joint is provided which supports 10 a plane 30. A corresponding symmetric axle 24 is, moreover, provided carrying a plane 31. The plane 30 may be adjusted by the control members 32, 33 and the axle 23 carrying the plane 30 may be swung and if necessary rotated by means of 15 the control members 26, 27 and 28. In special cases, further control members, for instance control members actuated by restoring springs, may be provided. The plane 31 and the axle 24 may be adjusted in a manner similar to that described 20 in connection with the axle 23 and the plane 30. The control member 29 corresponds to the control member 28. The other control members are not shown in the drawings. 31' illustrates a position of adjustment of the plane 31. The axle of 25 the plane 31 as well as the essential part of the control mechanism is arranged upon the supporting mast 25.

By means of the novel steering and/or stabilizing plane a great many aeronautic requirements 30 may be fulfilled. The quick and various adjustments of the planes enable the pilot in case of fast flying airplanes to effect changes of directions of all kinds with greater speed and safety as well as to increase the lifting capacity with 35 regard to known flying machines and to simultaneously effect lifting with more safety. In case of dirigible balloons, lifting screws etc. weaker air current may be utilized than hitherto.

What I claim is:

1. An airplane comprising a main supporting plane and a plurality of additional planes disposed above and spaced from said main supporting plane and adapted to be tilted about an axis transverse to the direction of flight, each additional plane comprising an individually movable part, and said parts being interconnected by a plurality of pivotal connections about which they are adapted to be individually tilted, and means 5 for controlling the movement of said additional planes about said transverse axes.

2. An airplane according to claim 1 wherein one of the additional plane parts is universally mounted on the structure of the airplane and the remaining additional plane parts are adjustably mounted on said first one of said plane parts. 15

3. An airplane comprising a body, a supporting plane connected to said body, a plurality of substantially upright shafts movably mounted on said body, additional controlling planes pivotally mounted on said shafts above said supporting plane and spaced therefrom, and means for adjusting the position of the shaft with respect to 20 the plane and for tilting said additional planes.

4. An airplane comprising a body, a supporting plane connected to said body, a pair of skewed upstanding shafts swingably mounted by a universal joint on said body and adapted to be rotated, additional controlling planes arranged on 30 each of said shafts above the supporting plane and spaced therefrom and adapted to be tilted by means of said shaft, means for independently tilting said additional flaps, and means for independently controlling the universal movement of 35 said shaft.

CHARLES ROGER ANNE
MARIE DE ROUGÉ.
